UNITED STATES PATENT OFFICE.

ADOLF H. JUNKERS, OF RHEYDT, GERMANY.

PROCESS AND APPARATUS FOR SATURATING YARN ROLLS WITH DYES.

Application filed August 20, 1925, Serial No. 51,454, and in Germany June 14, 1924.

This invention relates to improvements in processes of and apparatus for saturating yarn rolls with dye, the object being to provide an improved process and apparatus whereby the roll is saturated with the dye in minimum time, as the dye is everywhere introduced to the roll and the necessary pressing and extending of each part of the yarn is attained, which process is especially adapted 5 for the complete saturation of the yarn cross section with dyes. For this purpose the yarn is wound onto a sleeve of relatively large diameter with an inner cross section, which is sufficient for forcing more dye through the 10 yarn than is needed; the corresponding large circumference of the roll sleeve is able to receive a great number of perforations, so that all the yarn parts are uniformly saturated by the dye. The end faces of the rigid sleeves are 15 so constructed as to tightly fit against plane surfaces. In the said pressing device the windings are so confined on both sides, that the dyes cannot laterally escape. Because of the strong pressure the yarn windings press 20 each other, and this may still be favored by using intermittent pressure. It is further necessary to saturate the outer yarn windings upon which no favorable pressure reaction by 25 surrounding windings is exercised. This is done by repeatedly pressing the dye radially from the inner to the outer circumference 30 through the yarn roll and kneading the outer circumference of the yarn roll during said 35 pressing.

In the drawing an apparatus for the realization of the said process is shown,

Fig. 1 is a longitudinal section, and

Fig. 2 is a cross section.

On a roll sleeve *a*, having a large diameter 40 with respect to the diameter of the whole yarn roll, the yarn windings *b* are arranged for saturation. The roll by a screw *c* is so pressed between two discs *d*, that the end faces of the sleeve and of the winding are tightly 45 covered. The dye penetrating from the sleeve to the winding is thereby prevented from flowing out sidewise and is constrained to stream radially through all the windings.

According to Fig. 1 for the introduction of 50 the dye a hollow shaft *e* is so arranged, that it supports on one end the roll and on the other end a dye supply pipe. The shaft *e* is slowly turned during the dye pumping operation by means of worm gears *g'*, *h*, respectively on the shaft *e* and a power shaft *i*. At the 55 same time the outer circumference of the roll

may be manually kneaded. As shown in Fig. 2, a roller *f* is provided on a swingable hand lever, so as to be pressed by hand against the yarn roll, and hereby a good saturation of the outer winding can be attained. The superfluous dye coming out from the circumference of the roll falls into a vat *g*, and from there it flows back to the pump.

The vat has a drainage opening *k* which in practice may be closed by a plug.

My improved process can be carried out in a very short space of time and enables very concentrated dye to be used without waste. No more dye than is needed for the treatment 70 of each roll need be employed, and my process enables uniformity of the dyed product to be secured.

The apparatus is cheap and simple in construction and in practice several such machines can be operated by one man.

I claim:

1. A process for saturating yarn rolls with dyes, consisting in forcing the dye radially from the inner to the outer circumference 80 through the yarn roll and simultaneously kneading the outer circumference of said yarn roll.

2. An apparatus for saturating yarn rolls 85 with dyes, comprising in combination a hollow perforated sleeve adapted to support a yarn roll, a lever having means arranged to be pressed against the outer circumference of said yarn roll, means for supporting said roll sleeve and said lever rotatably with respect to each other, a round roll sleeve axis, and means for feeding dye to the interior of said sleeve.

3. An apparatus for saturating yarn rolls 95 with dyes, comprising in combination a hollow perforated sleeve adapted to support a yarn roll, a lever having means arranged to be pressed against the outer circumference of said yarn roll, a hollow rotatable shaft supporting said sleeve, and means for feeding dye to the interior of said hollow shaft and sleeve.

4. An apparatus for saturating yarn rolls 105 with dyes, comprising in combination a hollow perforated sleeve adapted to support a yarn roll, a lever, a roller on said lever, said lever being arranged to press said roller against the outer circumference of said yarn roll, means for supporting said roll sleeve and said lever rotatably with respect to each other around the roll sleeve axis, and means for feeding dye to the interior of said sleeve.

5. An apparatus for saturating yarn rolls with dyes, comprising in combination a hollow perforated sleeve adapted to support a yarn roll, a disc on said sleeve, means for feeding dye under pressure to the interior of said sleeve and through said disc, a second disc fitting to the end face of said sleeve, means for pressing said second disc against said end face, means for rotating said sleeve and means 10 arranged to be pressed against the outer circumference of said yarn roll.

6. An apparatus for saturating yarn rolls with dyes, comprising in combination a hollow perforated sleeve adapted to support a

yarn roll, a disc on said sleeve, a hollow shaft 15 axially projecting from said sleeve and said disc, a casing forming a vat below said sleeve, a bearing on said casing for said shaft, a second disc fitting to the end surface of said sleeve, an arm on said casing, extending to the 20 end face of said sleeve, a pressure screw in said arm for pressing said second disc against said sleeve end, means for rotating said shaft and sleeve, and means arranged to be pressed against the outer circumference of said yarn 25 roll.

In witness whereof I affix my signature.
ADOLF H. JUNKERS.
